DIVIDER FOR DRAWERS

Claude B. Cooper, Watertown, Mass.

Application August 10, 1931. Serial No. 556,251

11 Claims. (Cl. 129—16)

This invention relates to divider panels for index trays or drawers and has particular reference to divider panels which may be used as index stops, but which permit extension of the 5 file.

The instant invention provides a drawer panel or divider which is of simple and rugged construction and which is designed to give long and continuous service. It also provides a divider 10 panel which may be used to separate one portion of a file from another and at the same time permit of flexibility and separation of the various portions of the indexed material; and a divider, which will retain and maintain the indexed 15 material in an upright position; a divider panel, which when flexed or pushed to one side under pressure will return to and assume a fixed position in the index drawer or file; a divider panel which when flexed or pushed to one side in the 20 index drawer or file with the indexed material contained in the drawer or file will cause such indexed material to return to an upright position in the drawer or file.

In the drawings:

25 Fig. 1 is a side elevation of the instant device used in conjunction with a drawer or tray of a filing cabinet or the like.

Fig. 2 is a section on line 2—2 of Fig. 1.

Fig. 3 is a view in perspective of a bearing 30 member of the device.

Fig. 4 is a view in perspective of a special type of anchoring member of the device.

Fig. 5 is a side elevation of a modification of the device.

35 Fig. 6 is a section taken on line 6—6 of Fig. 5.

Fig. 7 is a fragmentary showing of another modification of the device.

Fig. 8 is a section of a spring retaining member shown in Fig. 7.

40 Fig. 9 is a fragmentary plan view of the special spring containing mechanism illustrated in Fig. 8.

Fig. 10 is still another modification of the device in elevation.

Fig. 11 is a fragmentary view showing the special anchoring means.

Fig. 12 is a view on line 12—12 of Fig. 11.

Fig. 13 is a view in perspective of the special anchoring means.

50 Fig. 14 is a view in perspective of a lower corner of an index tray or drawer showing means whereby the special divider panel may be anchored therein.

Fig. 15 is still another modification of the improved divider panel in elevation.

Fig. 16 is an enlarged section on line 16—16 of Fig. 15.

Fig. 17 is an enlarged view in perspective of the anchoring lever arm.

Fig. 18 is a view in perspective of a side of the 60 index drawer showing means for locking and supporting the drawer panel in a rocking relationship.

Referring more particularly to the drawings, the side walls of an index drawer or tray are 65 designated generally at 20. The drawers are provided with longitudinally extending channels 21 formed at the juncture of the side walls 20 and the bottom 22 of the drawer. The drawer is also provided with the usual channel or trough 70 23 placed centrally of the drawer in which the usual locking bar or rod 24 is placed for guiding a divider or follower and bracing the cabinet.

An index divider panel or partition 25 is formed to fit within the index drawer and to permit of 75 free movement of the panel therein. Means are provided for attaching the panel or partition within the drawer whereby the panel may be rocked or moved from side to side. Outwardly extending ears 26 are formed upon the lower portion of the panel and provide suitable members upon which the anchoring members 27 (Fig. 4) may be readily attached in any desirable fashion, as for instance by welding or by means of screws or rivets. The upper portion of the panel is provided with means for receiving a bar member 80 movable with respect to the panel; in Fig. 1, and a folded or bent portion 28 is provided which is adapted to receive for slidable movement therein the transverse bar member 29.

The upper folded portion 28 is attached adjacent its lower edges to the upper edge of the panel 25 as shown in Fig. 2 by any desirable method, as for instance by spot-welding. The upper edge of the panel or partition 25 projects between the 85 lower edges of the folded portion 28, which are contracted about the panel 25 to form a closed portion serving to retain the slidable bar 29 within predetermined limits. An aperture or slot 30 is provided in the upper edge of the panel 25 and in the lower portion of the folded member 28 which allows a portion of the bar member 29 to serve as a handle or grip for manual movement of the slidable bar member vertically within the folded portion 28.

The slidable bar member 29 forming part of the partition is advantageously made of sheet-metal, folded to form a double thickness as shown in Fig. 3, although other forms of fabrication may be employed, and is provided at each end 100 105 110

adjacent its upper edge with downwardly projecting fingers 31 spaced from the main body of the bar. Pin-receiving means are provided on the fingers 31 such as the bulged portions 32, 5 and other bulged portions 33 are provided on an adjacent portion of the body member aligned with the bulged portions 32 to receive a pin 34 upon which bearing means such as the roller member or bearing member 35 may be mounted 10 to support the slideable bar 29 upon the upper edge 36 of the sides 20 of the drawer or tray, as shown in Fig. 1. Means are provided for retaining bar 29 against the upper edge of the panel 25, and to this end an aperture 37 is provided adjacent each end of the lower edge of member 29 for receiving and retaining the upper end of a coiled spring 38 which has its lower end attached to a portion of the panel member 25, as for instance to the projecting ears 26.

20 The anchoring members 27 are secured as mentioned above to convenient portions of panel 25 as for instance to the projecting ears 26, and each is adapted to cooperate with a fixed portion of the drawer or tray and retain the panel member at a desired position within the drawer. To this end, the shank 39 of the anchoring member is bent angularly from the main portion of the body of the panel 25 and is provided with a horizontal foot portion 40 and an upwardly 30 projecting toe member 41. This anchoring member is adapted to engage with and receive one of a number of convenient strap portions 42 (Fig. 2) which have been formed within the channels 21 at the bottom of the side walls and 35 anchor the panel in a fixed position within the drawer so that it is rockable about the anchoring point.

Thus, when the panel is inserted in an index tray or drawer to act as a divider panel or stop member, the panel is ordinarily inserted angularly within the drawer and the anchor members 27 engage a pair of strap members 42 upon the shanks 39 of the anchors and slide thereagainst to come to rest upon the foot portions 40 thereof. Since the bar member 29 is normally of greater length than the width of the panel member the downwardly projecting fingers 31 and portions of the bearing members 35 extend beyond the upper edges 36 of the drawer and the bearing members 35 rest thereon. Under influence of the tension of the coil springs 38 the bearing members 35 move upon the upper edges of the drawer and the divider panel is caused to assume an upright position in the drawer as shown in Fig. 2 in full lines while the broken lines indicate the rocking movement thereof. Where the panel is inserted in an index drawer between indexed material, the panels may be pushed to one side or the other, as indicated by the dotted lines in Fig. 2, so as to provide ready access to the filed material and provide the advantages of a flexible filing system where the filed material is relatively extensible.

When the filing operator has completed work 65 within the filing drawer or tray the influence of the coiled spring members 38 and the bearing members 35 cause the divider panel to assume an upright position and automatically re-arranges the filed material in a vertical position within the drawer.

70 A modified form of construction of a panel is shown in Fig. 5 wherein the means for insuring contact between the bearing members 35 and the upper edges 36 of the sides of the drawer comprises a leaf spring 45 which has bearing contact

against the upper edge of the bar member 29 and against the upper edge of the folded portion 28 of the panel and is advantageously interposed within the folded portion 28. The leaf spring 45 is retained in a fixed position within the folded member 28 by providing a spot or indentation 46 as shown in Fig. 6 to secure a curved portion 47 of the leaf spring and prevent displacement thereof. In all positions of the panel removed from the vertical greater pressure is exerted by the leaf spring upon bar 29 and hence also greater lateral pressure exerted upon the bearing members 35 which have movable contact with the upper edges 36 of the side walls of the drawer. Under such conditions, the panel is caused to move to a position of lessened lateral pressure and hence assumes an upright position in the tray and causes re-arrangement of indexed material therein so that the latter assumes a vertical position within the index drawer.

Another modification of the panel and resilient means is shown in Figs. 7, 8 and 9 wherein bulged portions 50 are provided within the folded portion 28 of the panel and are adapted to receive therein the telescopic cup members 51 (Fig. 8). Each 100 upper telescopic member 51 is secured or wedged within the bulged portion 50 of the folded member 28 of the panel and is adapted to receive therein a lower slideable telescopic member 52 which has bearing contact at its lower edge upon 105 a convenient portion of the bar 29. As shown in Fig. 7, this modification may be formed by providing slots 53 within the upper portion of the bar member 29 for receiving the lower telescopic portions 52 and for retaining these members in 110 telescoped relation with the upper members 51 against inadvertent displacement.

Compressed coil springs 54 are provided within the upper and lower telescopic members 51 and 52 so that a downward pressure is exerted at all 115 times upon the transverse bar member 29 and when the panel is inserted within an index drawer or file the bearing members 35 are caused to exert pressure upon the upper edges 36 of the side walls 20 of the drawer and retain the panel normally in an upright and vertical position therein. It will be readily apparent that this modification of the panel permits of rocking or swaying movement of the panel.

Another modification of the invention is shown 125 in Fig. 10 wherein the panel 55 is provided with an upper portion 28 formed as described under Fig. 1 and provided with a transverse cross-bar 29 movable therein, also of the type as described above in Fig. 1. The lower edge of the panel 55 130 is provided with a curled or rolled edge 56 thereon (Fig. 12) providing a sleeve into one end of which is inserted the anchoring pin 57. An anchoring pin 58 movable within the sleeve 56, is provided in the other end which is actuated by 135 a spring 59. Thus, as shown in Fig. 11, the spring 59 is provided within the lower rolled edge 56 of the panel and has bearing contact at one end against a stop member which may be in the form of a lug 60 cut and pushed inwardly from the side 140 of the panel. The other end of spring 59 has bearing contact with one end of the pin stop member 58. A slot 61, formed within a convenient portion of the rolled sleeve or edge member 56 provides a suitable receiving means for a stop 145 or tail piece 62 formed at the rear end of the anchoring pin 58. Thus, anchoring pin 58 may be moved within the sleeve or rolled lower edge 56 of the panel and be retained therein by engagement of the stop member 62 with the edges 150

of the aperture 61 formed within the sleeve or rolled edge.

Suitable receiving and engaging means are provided for the anchoring pins 57 and 58 for retaining the panel within the index drawer. In Fig. 10 an apertured strip member 63 is provided upon the inner side walls of the index drawer adjacent the bottom channel member 21 thereof for receiving the pin anchoring members. The strip 63 is attached to the side walls in any convenient manner to form a rigid and secure anchoring means for retaining the panel within the drawer and is further provided with the spaced apertures 64 whereby the panel can be placed within the index drawer in a plurality of positions longitudinally thereof.

In inserting the panel within the drawer the movable stop member 58 may be placed within a convenient aperture 64 and a pressure applied to the panel whereby the panel and sleeve 56 will move upon the pin member 58 toward the side of the index drawer whereby the companion pin member 57 may be inserted in a suitable anchoring aperture formed in the companion strip 63 upon the other side of the drawer. Removal of the panel is accomplished readily by exerting sidewise pressure upon the panel whereby the pin moves within the slot a sufficient distance to disengage the companion pin 57 from its anchoring slot member so that the panel may be readily removed.

Spring means 65 are provided to connect the bar 29 with the lower end of the panel, as at 66 and 67 whereby sufficient pressure is insured to cause engagement of the roller means 35 upon the upper edges 36 of the side walls of the drawer. Under such conditions a panel of the type described and shown in Fig. 10 will assume an upright position in the index drawer and will cause a vertical positioning of the material filed therein. This particular modification is adapted for use in index drawers currently in use by securing the apertured strip 63 adjacent the bottom edge of the side walls of the drawer.

A modified form of anchoring pin is shown in Fig. 14 wherein a divider panel 55 is formed with a rolled lower edge 56 which is adapted to receive and retain a pin member or anchoring member 70. In this modification the lower portion 71 of the side walls 72 of the index drawer are offset to receive the slotted member 73. This member is placed adjacent to the lower edge of the side wall and conforms to the contours thereof so that a tightly fitted and securely held member is provided with spaced slots 74 for receiving the anchoring pin 70. In order to retain the anchoring pin 70 within the slotted portion 74, the pin 70 is provided with an enlarged end 75 so that when the pin is inserted within the slot sidewise movement of the panel will not displace the anchoring pin.

This type of divider panel is retained in secured position within the drawer and anchored within one of the retaining slots 74 by means of the coiled spring 76 which is attached to a convenient portion of the anchoring pin and to the slideable bar member as in the first form.

In order to insert the panel in the index drawer it is first inserted into the drawer at an acute angle to the side walls so that pin 70 can be subsequently inserted within the off-set portion 71 of the side wall by moving the panel toward transversely extending relation in the drawer and pin 70 moved upwardly into a slot 74 in one side of the drawer and the panel then moved into a transversely extending position in the drawer so that

the companion pin will similarly engage within a slot member on the other side of the drawer and be retained therein by the enlarged end thereon.

Fig. 15 depicts an embodiment of the present invention wherein an index drawer 80 is provided with side walls 81 which are formed with apertured recessed portions 82 longitudinally of the drawer and which are placed substantially centrally of the drawer thereof. Divider panels 83 are provided to fit within the index drawer and be retained therein in a normally upright and vertical position but which are adapted for pivoted movement therein.

The panels 83 are formed from suitable material such as folded sheet-metal to provide a space between the two sides of the panel for receiving the movable arms 84 and 85 which pivot about the pins 86 and 87, respectively. These arms are formed with downwardly projecting fingers at one end which are formed with convenient bulges, as in Fig. 3, for receiving a pin member 34 and bearing member 35.

The upper central portion of the divider panel is formed with a recess therein through which the pivoted lever arm 88 projects and in which the arm is manually operable. This arm is pivotally mounted at 91 and has attached thereto a supporting lever arm 90 at a point below the pivot point 91 so that movement of the lever arm will cause a movement of the arm 90 relative to the panel 83. Similarly, another supporting arm 92 is pivotally attached to the lever arm 88 at a point above the pivotal attachment of arm 88 to the panel 83, so that movement of the lever arm 88 will move arm 92 relative to the panel. Thus manual movement of arm 88 produces movement of arms 90 and 92 so that the ends thereof are substantially flush with the side edges of the divider panel.

The supporting arms 90 and 92 are formed, as shown in Figs. 15 and 17, with a projecting finger 101 formed thereon at one end which is provided with an upwardly extending knife edge 93 whose purpose will be made more clear hereinafter, and suitable attaching means 94 at the other end thereof.

Stop members 95 are provided within the folded portions of the panel and the upper edges 96 thereof serve as stops and retaining members for arms 84 and 85 when the divider panel is removed from the index drawer. Lower edges 97 thereof also serve as stop members for the arms 90 and 92 and at the same time, these members serve as reinforcing members for the panel and act to retain the same in undistorted form and condition. Coil springs 98 and 99 are provided attached to the pivoted arms 84 and 85 at one end thereof and to the supporting arms 92 and 90, respectively, at the other end.

Thus it will be clearly seen that in order to insert the divider panel into the index drawer the lever arm 88 is moved in a direction which will withdraw the arms 90 and 92 within the divider panel which may then be inserted within the drawer. The bearing members 35 will form contact upon the upper edges 36 of the side walls 81 of the drawer and a downward pressure upon the inserted panel will bring the supporting knife edges 93 in alignment with the apertures 100 formed within the recessed portion 82 upon the sides of the drawer. Movement of the lever arm 88 will cause the supporting arms 90 and 92 to project outwardly from the panel and each finger 101 will project into an aperture 100 as shown in Fig. 18. Upon release of the pressure on the top of the

panel the knife edges 93 will produce rockable contact with the side wall to form a pivot for panel 83.

5 It is thus clearly seen that the various forms and modifications of the instant invention provide a divider panel for drawers of filing cabinets and the like which possesses the advantages that it functions as a stop member for the drawer and at the same time provides the advantages of a flexible or extensible filing cabinet, in that the elements are movable and adapted to be adjusted to embrace various kinds of filed matter.

10 Other forms and modifications of the invention are included in the appended claims.

15 What is claimed is:

1. In combination with an index drawer of a file, a divider panel for the drawer having parts for detachable connection to parts carried by the drawer to detachably hold said panel in the drawer, a bar movably mounted adjacent a marginal portion of the panel, bearing means on the bar for contact with a portion of the drawer, and means for resiliently holding said bearing means in contact with the drawer and cooperating to retain said panel in connected relation with the drawer for relative swinging movement about said connection.

2. In combination with an index drawer of a file, a divider panel for the drawer, comprising an upper folded portion, a bar adapted to fit movably within said folded portion, bearing means at either end of said bar adapted to engage with the side walls of the drawer, anchoring means attached to the lower edge of the panel, means formed upon the index drawer for engaging said anchoring means, and resilient means engaging said bar and said panel for retaining the panel normally in an upright position within the drawer.

3. In combination with an index drawer of a file, a divided panel for the drawer, a bar projecting beyond the side edge of said panel, said projecting portion being movable relative to said panel, bearing means upon said bar for engagement with a portion of said index drawer, anchoring means attached to said panel for holding the panel within the drawer and permitting pivotal movement thereof, means formed upon the drawer for receiving said anchoring means in pivotal engagement, and resilient means coacting with the panel and bar for retaining the panel in the drawer in a normally vertical position.

4. In combination with an index drawer of a file, a divider panel for the drawer, comprising a movable bar retaining means attached to the panel for limiting movement of the bar, bearing means upon said bar for engagement with a portion of said index drawer, anchoring means pivotally connecting the panel to the drawer and resilient means engaging said bar and said panel for yieldably retaining the panel normally in an upright position within the drawer.

5. In combination with an index drawer of a file, a divider panel for the drawer, comprising a folded upper portion, a bar movable within said folded portion, bearing means upon said bar for engagement with the drawer, anchoring means upon said panel, means upon the drawer for receiving said anchoring means, and a leaf spring engaging said folded portion of the panel and

said bar for retaining the panel normally in an upright position within the drawer.

6. In a panel for insertion in a drawer of a filing device, a divider panel adapted to be anchored within the drawer, a bar associated with said panel and movable relative to the panel, bearing means upon said bar for contact with and movement upon a portion of the drawer, means for anchoring the panel in the drawer, and means on the panel yieldably urging the bar and anchoring means toward each other.

7. In a panel for insertion in a drawer of a filing device, a panel member, a bar associated with said panel member and movable relative thereto, bearing means upon said bar for engagement with a portion of the drawer, means for anchoring the panel member in the drawer, and yieldable means connected to the panel member and the bar for retaining the panel in an upright position in the drawer.

8. In a panel for insertion in a drawer of a filing device, a panel member, a bar retained by the panel member and movable relative thereto, means upon the bar for engagement with a portion of the drawer, means for anchoring the panel member in the drawer, and resilient means connected to the panel member and bar for retaining the drawer and panel member in movable assembled relation and yieldably resisting movement of the panel member from its normal position.

9. A divider panel for insertion in a drawer of a filing device, comprising a panel member, a bar connected to the panel member and movable relative thereto, bearing means upon said bar for engagement with the drawer, anchoring means upon said panel member, means upon the drawer for receiving said anchoring means, and coiled spring means having bearing contact with said panel member and said bar for yieldably retaining the panel member normally in an upright position within the drawer.

10. A divider panel for insertion in a drawer of a filing device, comprising a panel member, a bar connected to said panel member and movable relative thereto, bearing means upon said bar for engagement with the drawer, an anchoring pin movably mounted on said panel member, means upon the sides of the drawer for engaging said anchoring pin whereby the panel member may rock thereon, and resilient means having operative relation to the bar and drawer for retaining the panel member normally in an upright position within the drawer.

11. A divider panel for insertion in a drawer of a filing device, comprising a panel member, means connected to said panel member and movable relative thereto, said motion being restricted by portions of said panel member, said means being adapted for engagement with said drawer, anchoring bars movably mounted on said panel member, means upon said drawer for engaging said anchoring means whereby the panel member may rock thereon, means for manually moving said anchoring bars, and resilient means having operative relation to said drawer-engaging means and said anchoring bars for retaining the panel member normally in an upright position within the drawer.
